Attorney

UNITED STATES PATENT OFFICE

CLARENCE WORMS, OF ST. LOUIS, MISSOURI

RADIATOR ORNAMENT

Application filed April 15, 1931. Serial No. 530,241.

My invention relates to improvements in radiator ornaments, and more particularly to a toy airplane to be used as such an ornament, and has among its objects, the production of 5 such a device, which will simulate the banking effect of an airplane.

Other objects of my invention are to construct such a device which will be neat and attractive in appearance, simple in construction, sturdy, interesting, and efficient and satisfactory for use wherever found applicable.

A still further object of my invention is to provide means for mounting an ornament 15 of the kind described, upon a radiator or the like, and permit of the pivotal movement of the ornament about its mounting, in a plurality of planes at an angle to one another, to thereby cause the ornament to move freely 20 about said support.

Many other objects and advantages of the construction herein shown and described, and the uses mentioned, will be obvious to those skilled in the art to which this invention 25 pertains, from the disclosures herein given.

To this end, my invention consists in the novel construction, arrangement and combination of parts herein shown and described, and more particularly pointed out in the 30 claims hereto appended.

In the drawing, wherein like reference characters indicate like or corresponding parts throughout the views,

Figure 1 is a front elevation of my improved device as mounted upon a radiator, and showing its appearance when banking to one side; and

Figure 2 is a perspective view of the framework of the same, with the outer body removed.

Referring more particularly to the drawing, wherein I have illustrated a preferred embodiment of my invention, A represents the radiator cap of an automobile or the like, 45 and to which it is desired to attach my ornament, which may be in the form of the airplane B as shown. The fuselage of the plane is indicated at 1, the same having side wings 2-2 extending laterally therefrom, and the 50 rudders being shown at the rear at 3.

When a full-sized airplane is in motion overhead, and the airplane circles, it does what is termed "banking," which means that one side wing is advanced relative to the other and the advanced wing is elevated above the other. Therefore, if the ornament that is placed upon the radiator is to be an airplane, it is desirable that said airplane simulate the movements of the real, full-sized airplane, as much as possible, and especially that it have 60 the banking appearance of the latter.

The frame-work of the ornament may be made of any suitable size, shape and material, as shown at 4, wherein it is indicated as being formed and shaped of wire, and intermediate 65 the front and rear of the same it is formed with side bearings 5-5. An axle 6 is provided, having trunnions 7-7 at its ends, loosely inserted through the bearings 5-5 of the frame-work 4, to permit free pivotal 70 movement of the latter in a substantially vertical plane.

The axle 6 is pivotally mounted intermediate its ends, as at its center, so that the same may be rotated in a plane inclined relative 75 to the horizontal and vertical planes, or in other words, in an oblique plane. To do this, a supporting plate 8 is provided, to form a bearing for the axle, this plate being formed so as to lie in an oblique plane when in 80 mounted position upon the radiator.

The axle is pivotally secured in place upon the plate as on a bearing, by means of any suitable securing means, as by the pin 9 projecting from the plate and through the center of the axle. Therefore the axle may rotate in a plane intermediate the vertical and horizontal planes, or in an oblique plane.

Any object carried by the axle and pivotally secured to its ends, will have a freedom of 90 movement in a substantially vertical plane (about the trunnions), and in an oblique plane (about the pin 9). This pivotal movement of the ornament in its support, about the longitudinal axis, and about an axis intersecting this longitudinal axis, will permit the ornament to bank, and thus if the ornament is an airplane, a life-like effect will be had, thereby greatly increasing the desirability of 95 the device.

In order to limit the horizontal rotation of the ornament, and also to overcome any tendency of the ornament to tip over rearwardly, I provide a flexible element 10 secured to the 5 forwardly projecting end of the ornament, the other end of said element being secured to a fixed element, as to the supporting rod 11 between the radiator cap and the plate. This supporting rod is secured at its upper end to 10 the plate 8 and is of such a length and is inclined as desired, the lower end being suitably secured to the radiator cap.

Obviously, the ornament may rotate in the plurality of planes described, and if the object is an airplane, it performs banking, one side edge of the airplane advancing in front of the other side edge and being elevated above the latter.

Having thus described my invention, it is 20 obvious that various immaterial modifications may be made in the same without departing from the spirit of my invention; hence I do not wish to be understood as limiting myself to the exact form, construction, 25 arrangement and combination of parts herein shown and described, or uses mentioned, except as limited by the state of the art to which this invention appertains, or the claims hereto appended.

30 What I claim as new and desire to secure by Letters Patent is:

1. In a device of the kind and in combination, an ornament; a support therefor; and means for mounting said ornament on said 35 support and including an axle having its ends pivotally connected to and supporting said ornament, and means for pivotally mounting said axle intermediate its ends on said support on an oblique rotational axis so 40 that the axle may rotate about its axis in a plane intermediate the vertical and horizontal planes.

2. In a device of the kind described and in combination, an ornament; a support therefor; means for mounting said ornament on said support and including a substantially horizontally extending axle pivotally connected to and supporting said ornament; and means for pivotally mounting said axle on 50 said support so that the axle may pivot in an oblique plane.

3. In a device of the kind and in combination, a toy airplane; a support therefor; means for movably mounting said ornament 55 on said support so that it may be banked, and including an axle loosely pivotally supporting said airplane so that it has movement in a vertical plane; and means for pivotally mounting said axle intermediate its ends so 60 that the latter may rotate in a plane oblique to the vertical and horizontal planes.

4. The combination with a supporting rod; of an ornament; an axle for mounting the latter for pivotal movement in a vertical 65 plane; and means intermediate the ends of

said axle for mounting the latter on said rod for pivotal movement about an axis intersecting the axis of said axle.

In testimony whereof I have affixed my signature.

CLARENCE WORMS.
